US00D888252S

(12) **United States Design Patent** (10) Patent No.: **US D888,252 S**
(45) Date of Patent: ** Jun. 23, 2020

(54) **TRANSCUTANEOUS ANALYTE SENSOR APPLICATOR**

(71) Applicant: **DexCom, Inc.**, San Diego, CA (US)

(72) Inventors: **Warren Terry**, Poway, CA (US); **Patrick John Castagna**, San Diego, CA (US); **David A. Keller**, Encinitas, CA (US); **Young Woo Lee**, San Diego, CA (US); **Joseph J. Baker**, Vista, CA (US); **Randall Scott Koplin**, Middleton, WI (US); **Andrew Joneich**, Madison, WI (US)

(73) Assignee: **DexCom, Inc.**, San Diego, CA (US)

(**) Term: **15 Years**

(21) Appl. No.: **29/653,761**

(22) Filed: **Jun. 18, 2018**

CLAIM

The ornamental design for a transcutaneous analyte sensor applicator, as shown and described.

DESCRIPTION

FIG. 1 is a top, front, and right-side perspective view of a transcutaneous analyte sensor applicator showing our design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines illustrate portions of the transcutaneous analyte sensor applicator that form no part of the claimed design.

1 Claim, 4 Drawing Sheets
